UNITED STATES PATENT OFFICE

ADOLPH LANGSNER, OF CHICAGO, ILLINOIS, ASSIGNOR TO EUGENE DIETZGEN COMPANY, OF CHICAGO, ILLINOIS, A CORPORATION OF DELAWARE

DEVELOPING APPARATUS

Application filed February 20, 1928. Serial No. 255,637.

My invention relates to developing apparatus for developing light sensitive material such as paper and the like, by means of the action of chemically active developing gas such for instance as ammonia gas.

One of the objects of my invention is to provide a compactly built commercial type of developing cabinet wherein the light sensitive material may be inserted and withdrawn and wherein it is subjected to developing action of gases given off within the cabinet and wherein provision is made for cutting off the escape of the gases from the container within the cabinet while the door of the cabinet is being opened or closed in order to insert or withdraw the light sensitive material.

Another object of my invention is to provide in a type of developing apparatus of the above character, sufficient room within the cabinet above the pan containing the liquid for giving off gases so that such gases will rise to the top of the cabinet to provide a developing zone within which a support or basket for the light sensitive material may be located for the developing action and the device further includes a door for the insertion and withdrawal of the light sensitive material which door is constructed and arranged so that the basket or work support may be raised and lowered within the cabinet and above the tank so as to be positionable at a point opposite the door or to a point substantially at the top of the cabinet for the developing action and therefore my invention also includes the arrangement of a relatively flat pan or container for the developing liquid at the bottom of the cabinet together with a closure for the top of the pan operable when the door of the cabinet is opened or closed to cut off or open the pan from the remainder of the cabinet so as to permit or preclude the rise of the gases into the cabinet and this closing member is of such nature as to provide sufficient room above the pan within the cabinet for the effective raising and lowering of the work basket and in addition is operable from a point without the cabinet.

An ancillary object of my invention resides

in the manner in which the closure for the pan is controlled from a point outside of the cabinet; and the manner in which the work basket is raised or lowered within the cabinet either by the opening and closing of the closing means for the pan or independently thereof or alternatively by the operation of the door of the cabinet if desired.

These and other objects of my invention will be apparent from a perusal of the following specification when taken in connection with the accompanying drawings wherein:

Figure 1 is a sectional side view of one form of my invention;

Figure 2 is a fragmentary view of the apparatus disclosed in Figure 1, showing the pan closing mechanism in shifted position;

Figure 3 is a side sectional view of still another modification of my invention; and

Figure 4 is the same device showing the pan closing means in closed position.

In the form of my construction shown in Figures 1 and 2 of the drawing, the cabinet 62 is provided with a door 64 hinged to the end wall as at 66 and I again provide the bottom of the cabinet with a relatively shallow pan 68 adapted to hold a quantity of liquid giving off chemically active developing gas such for instance as liquid ammonia giving off ammonia gas. This tank also connects with a flexible filling or discharge tube 70 at a point outside of the cabinet.

In the present construction I have provided an arrangement whereby the open top 72 of the cabinet may be closed by means of manually controlled shutters or closing means, operable from a point outside of the cabinet, and which closing members directly or indirectly control the raising and lowering of the work supporting means, to wit, the work holding basket, and in addition, I have provided the interior of the cabinet with means for guiding the basket in its raising and lowering operation. To this end, the inner portion of the cabinet is provided with brackets 74 and 76 connected to the side walls of the cabinet at the end corners of the tank and substantially above the same and these brackets also include centrally disposed

bracket portions 78 hereinafter described. The side brackets 74 and 76, there being four in number, one at each corner, in turn are connected to the under sides of inwardly extending flanges 80. The brackets 74 and 76 in turn provide supports for up-standing guide rods 82 and 84, there being four such guide rods, and these rods are connected to the top or roof 86 of the cabinet by means of 10 suitable nuts 88 whereby the four rods are detachably fastened in position at the corners and at the ends and within the cabinet. The work holder basket while capable of being of any openly constructed type so that the 15 gases may pass freely therethrough and so that the light sensitive material may be held therein, is preferably of open mesh or open wire construction 90 as shown in the drawings and is provided at each corner with a bifurcated lug 92 through which passes a rod 82 at the corner so that the basket is free to slide vertically within the cabinet and is guidingly supported by these rods 82 and 84. There is sufficient ease of action so that the basket may 20 slide easily up and down.

The closing means for the tank comprises two shutters 94 and 96 which shutters are rigidly mounted on shafts 98 and 100 having bearings on the intermediate bracket 102 and 30 these shafts 98 and 100 in turn are provided with gear sectors 104 and 106 respectively having intermeshing teeth and the gear 104 is provided with a lever-like handle 108 mounted on the shaft 98 on the outside of the 35 cabinet. Preferably a resilient strip 110 is mounted on the outside of the cabinet and may be shifted to a position so as to permit the handle to be lowered into the position shown in Figure 4 of the drawing while at 40 the same time will permit the handle to be raised into the position shown in Figure 3 and then released to hold the handle so as to maintain the shutters 94 and 96 in open position. It will be seen that these shutters are 45 of sufficient length to extend from shafts 98 and 100, which are immediately over the opposite ends of the central bracket 102 to points 112 and 114 which constitute the end of strips 116 and 118 which strips overlie the 50 brackets 74 and 76 and extend the width of the cabinet at the ends thereof. Thus when the shutters 94 and 96 are in closed position as indicated in Figure 4, the entire pan 68 will be enclosed within a secondary cabinet 55 120 and thereby the escape of gas from the pan will be cut off. In this position shown in Figure 4, the free ends of the shutters 94 and 96 do not touch the bottom of the work holding basket 90. However, when the handle 60 108 is operated and the shutters are raised through the intermediary of gear sectors 104 and 106, the free ends of the shutters will contact against the under side of the basket at opposite ends thereof and will forcibly raise 65 the basket against the action of gravity and

will push it upwardly to the top of the cabinet. At the same time the shutters will be in open position so that the gas is free to rise from the pan into the top of the cabinet and to develop the light sensitive material or paper carried in the basket. It will of course be understood that my present invention also contemplates the mounting of the shutters 94 and 96 in a manner such that instead of closing against strips 116 and 118 they will close directly upon the top edges of the pan in which event the central bracket 102 will preferably lie in the top plane of the pan or in fact, could be made as a supporting strip lying across this top plane of the pan and connected thereto and forming a sort of bridge thereacross. In either event, in the present instance, I have provided closing means for the pan which is constructed and arranged when shifted not only to control the escape of gas from the pan or the escape of the developing gas into the cabinet but will also control the positioning of the basket such that the raising and lowering of the basket into the gas developing chamber and therefrom to a position opposite the door 64. The broad aspects of my invention are not confined to the illustrated construction since other arrangements involving the broad principles of this inter-connection are within the contemplation of my invention. 90

Thus, it will be seen that this form of my invention provides a very facile manner of inserting or withdrawing the light sensitive material from the basket or work holder while at the same time automatically insuring the cutting off of the escape of the gas from the pan when the basket is lowered and on the contrary insuring the opening of the pan closing means when the basket is raised into developing position and this latter feature is a very important one since without some such means, an attendant might easily forget to open the pan closing means so that the light sensitive material would not be developed. At the same time, this construction permits of a relatively large developing zone above the door 64 into which the work holding basket may be shifted for the developing action. 105

Referring now to that modification shown in Figures 3 and 4 of the drawings, I therein provide a construction wherein the work holding means, specifically the basket, itself provides a closure for the gas escape openings in the pan containing the liquid developing medium. In addition, the work holding basket is interconnected with the door of the cabinet so that when the door is opened the basket is automatically shifted or rather lowered to a point where it is accessible from the open door while at the same time, and in addition thereto, the bottom of the basket forms a shutter for automatically closing the pan openings through which the gases are wont to 110 120 125 130

escape. In the construction illustrated in Figures 3 and 4, the cabinet 122 is likewise provided at its bottom with a relatively shallow pan 124 containing for instance, liquid ammonia 126, and provided with the usual filling and emptying means 128. In addition, the pan is provided with a top or at least the cabinet is provided with a top 130, which extends clear across the top of the pan. In the present instance, this top 130 is formed as a separate member and is supported upon brackets 132 and 134 which brackets in turn support the guide posts or rods 136 and 138. The upper ends of these rods are connected as at 140 and 142 to the top 144 of the cabinet, there being four such guide posts, two at each corner of the cabinet. This top 130 is provided with perforations 146 symmetrically arranged therein and through which the developing gas given off by the liquid ammonia 126 rises to the top of the cabinet and there forms a gaseous developing zone.

In the present instance, the work holding means, herein shown as the basket 148, automatically controls the opening and closing of the top of the pan 124 during the shifting movement of the basket. In the present construction, the basket is provided with lugs 150 and 152 which travel on the rods 136 and 138 to guide the basket vertically and the basket, although of open construction so as to permit the free passage of the gas therethrough to develop the light sensitive material, is provided with a bottom having imperforate portions 154 adapted to register with the openings 146 in the top 130 for the tank so that when in the lower position as shown in Figure 6, the tank will be wholly closed and no gas can rise therefrom into the cabinet. I preferably provide the bottom of the tank with openings 156 through which the gas is free to pass when the basket is raised out of contact with the top 130 of the tank, although this is not absolutely essential since the gas may pass through the sides and through the open top of the basket and have access to the light sensitive material.

I preferably provide means for automatically controlling this basket by the opening and closing of the door for the cabinet. To this end the outside of the cabinet is provided with guide strips 158 arranged in spaced apart relation on one end of the cabinet and the door 160 is mounted in said guide strips 55 to slide up and down in a vertical plane. The upper portion of this door is provided with a laterally extending lug 162 to which is connected a flexible connector 164 such as a rope or chain which passes over a pulley 166 preferably mounted on the outside of the cabinet and which flexible connector passes through an opening 168 in the top of the cabinet. This opening may be closed by any type of packing material such for instance as a flexible strip of rubber or felt so as to prevent

the escape of gas therefrom. The inner end of this flexible member 164 passes over a pulley 170 mounted on a bracket 172 within the top central portion of the cabinet and the end of this cable 164 is connected as at 174 with the middle portion of the basket. Hence when the door is lowered to closing position the cable 164 will be pulled to raise the basket to the upper portion of the cabinet and when the door is slid upwardly to open position the basket will be automatically lowered to fit upon the top of the pan and to close the openings thereof whereby to preclude the further escape of developing gas therefrom.

It will be apparent that by reason of the foregoing construction, I have provided a most convenient means for not only automatically controlling the escape of gases from the pan by the operation of the work holding basket but in addition, by means of the opening and closing of the door of the cabinet. Hence I have provided means for automatically controlling both of these operations at a point outside of the cabinet while at the same time affording a relatively large gas collecting zone within the cabinet into which the light sensitive material is raised prior to the developing operation.

Having thus described my invention, what I claim as new and desire to secure by Letters Patent is:

1. In a device of the class described, the combination of an enclosing cabinet, a relatively shallow pan therein adapted to hold a quantity of substance evolving chemically active developing gas, said pan having a perforated top through which the gas may rise into the cabinet, a sheet-like closing member for said pan having perforate and imperforate portions, said closing member being provided with means operable through the wall of the cabinet for shifting the same into closing and opening positions with respect to the opening in the cover, a door for said cabinet disposed slightly above the top of the pan and a work holding basket in said cabinet shiftable from a lower position opposite said door to a raised position substantially at the top of said cabinet.

2. In a device of the class described, the combination of an enclosing cabinet, means therein providing a source of chemically active developing gas, a door in said cabinet through which light sensitive material may be inserted into or withdrawn from the cabinet, means shiftably mounted in said cabinet for supporting light sensitive material therein, said means being constructed and arranged to control the escape of the developing gas into said cabinet, and being shiftable from material receiving and discharging position opposite said door to a developing position substantially within the cabinet and removed from said door, and means con-

trolled from a point outside of said cabinet for shifting said supporting means.

3. In a device of the class described, the combination of an enclosing cabinet having an inlet for the insertion of light sensitive material thereinto, a door for said inlet, a source of developing gas within said cabinet, means in said cabinet for moving light sensitive material from a point adjacent said door to a developing zone, and means automatically operated by the actuation of said door for actuating said work holding means and for controlling the escape of the developing gas into said developing zone.

4. In a device of the class described, the combination of an enclosing cabinet, a pan therein adapted to contain liquid ammonia, said pan being normally opened for the escape of ammonia gas therefrom, a work holding basket having a bottom formed with imperforate portions and adapted to overlie the top of said tank to close the same, said basket being shiftable toward the top of said cabinet to a developing zone and adapted when further shifted to be removed from said tank to permit escape of the gas therefrom, a door for said cabinet, said door adapted to be opened and closed and connections from said door to said work basket for raising and lowering the same upon the closing and opening of said door and vice versa.

5. In a device of the class described, the combination of an enclosing cabinet having a relatively shallow pan therein containing liquid ammonia, said pan having a perforated top, a work basket in said cabinet having a perforated bottom and also provided with imperforate portions adapted to close the perforations in the top of said pan, guides in said cabinet upon which said work basket is slidably and guidingly mounted, a slideable door for said cabinet and a flexible connection from said door to said basket, said connection being constructed and arranged to raise and lower said basket upon the lowering and raising of said door.

6. In a device of the class described, the combination of an enclosing cabinet, a pan therein adapted to contain material adapted to evolve chemically active gas for developing purposes, an open mesh work basket slidably mounted in said cabinet in a vertical plane and having a bottom provided with perforate and imperforate portions, said pan also having a cover provided with perforate and imperforate portions, the imperforate portions of said basket registering and controlling the opening and closing of said perforate portion of the cover of the tank, a pulley mounted in the top of said cabinet, a second pulley mounted on the outside of the cabinet adjacent the top, a door slidably mounted in guide-ways on said cabinet, said door being arranged to normally close an opening in said cabinet which opening is lo-

cated at a point below the top of said cabinet and slightly above the top of said tank, and a flexible cable connected to said door at one end and passing around the exterior pulley and through a slot in said cabinet and passing over the exterior pulley and connected to the work basket.

7. In a device of the class described, the combination of means forming a developing compartment having an opening for the insertion of light sensitive material into the compartment, a closure for sealing said opening, a shiftable support for receiving light sensitive material at the opening and carrying same into the compartment for development and means cooperating between said closure and said support whereby the latter is shifted when the former is moved.

8. In a device of the class described, the combination of a cabinet, provided with an opening for the insertion of light sensitive material, a door for closing the opening, shiftable means in said cabinet for supporting therein light sensitive material to be developed, means for liberating developing gas into the cabinet, said shiftable means being arranged to control the liberation of the gas and means for shifting said shiftable means upon the opening and closing movement of the door whereby to accomplish the controlling of the liberation of the gas.

9. In a device of the class described, the combination of a cabinet provided with an opening for the insertion of the light sensitive material into the cabinet, a door for closing the opening, shiftable means in said cabinet for supporting therein light sensitive material to be developed, means for liberating development gases into the cabinet, said shiftable means being adapted for controlling the liberation of the gas into the cabinet, being adapted when in one shifted position opposite the opening, to receive the light sensitive material introduced through the opening and to prevent the liberation of the gas into the cabinet, and means operable by the movement of the door for shifting the said shiftable means to a position substantially removed from said opening whereby to permit of the introduction of developing gases into the cabinet.

In witness whereof, I have hereunto subscribed my name.

ADOLPH LANGSNER.
